UNITED STATES PATENT OFFICE.

AUGUST WEDEIN AND JOHN PERCY STEVENS, OF MASON CITY, IOWA.

SHOE-HEEL.

1,347,883.

Specification of Letters Patent. Patented July 27, 1920.

Application filed February 11, 1920. Serial No. 357,993.

To all whom it may concern:

Be it known that we, AUGUST WEDEIN and JOHN PERCY STEVENS, citizens of the United States, residing at Mason City, in the county of Cerro Gordo and State of Iowa, have invented certain new and useful Improvements in Shoe-Heels, of which the following is a specification.

This invention relates to improvements in the heel parts of boots and shoes, and it consists in certain peculiarities of the construction, novel arrangement and operation of the various parts thereof, as will be hereinafter more fully set forth and specifically claimed.

The principal object of our invention is to provide a shoe heel which shall be extremely light in weight, very strong, simple and inexpensive in construction, durable and highly efficient in use, with its parts so made and arranged for ready application to or detachably interlocking with a boot or shoe, thereby enabling a heel to be quickly attached to and removed from the shoe to permit the heel to be renewed, or to allow different kinds, heights or styles of heels to be used, or for any other purpose.

A further object of the invention is to provide means for securely affixing the heel to the shoe in such a way as to firmly and securely hold its upper portion in close or tight contact therewith, or in such a manner as to prevent disfiguration of the shoe by the heel becoming separated therefrom at its upper portion or gapping, which is an objection to such heels which have heretofore been in general use.

A still further object of the invention is to provide means for co-operation with the insole and counter of the shoe as to firmly grip or clamp the same to the heel.

A still further object is to provide means to reinforce or strengthen the shank of the shoe in front of the upper portion of the heel thereby preventing the same bending as ordinarily occurs.

Still another object is to provide improved means for fastening the top-lift to the base of the heel.

Other objects and advantages of the invention will be disclosed in the subjoined description and explanation.

In the accompanying drawing, which serves to illustrate an embodiment of the invention—

55 Figure 1 is a rear view in elevation of a

portion of a shoe with a heel embodying our improvements mounted in place thereon.

Fig. 2 is a central vertical sectional view taken on line 2—2 of Fig. 1 looking in the direction indicated by the arrows. 60

Fig. 3 is a top plan view of the heel showing it detached from the shoe.

Fig. 4 is a bottom plan view of a portion of the heel part of a shoe, showing a plate mounted thereon for interlocking or detachable engagement with the upper rear portion of the heel, and 65

Fig. 5 is a bottom plan view of the base of the heel showing the recess therein for the reception of a washer or member to which 70 the top-lift may be secured.

Like numerals of reference refer to corresponding parts throughout the different views of the drawing.

The reference numeral 7 designates the 75 heel or rear portion of a shoe which shoe may be of the ordinary or any well known construction, and has secured to the bottom of the insole 8 near the rear portion thereof a plate or member 9 which as shown in Figs. 80 2 and 4 of the drawing is substantially semi-circular in shape and has its curved periphery located concentrically with the outer rear edge of the part 8 of the shoe, but at a slight distance therefrom. 85

This plate is by preference secured to the member 8 by means of a series of rivets or brads 10 some of which are arranged in a circular row at a distance from the curved periphery of said plate, thus permitting the 90 edge of the plate 9 or that portion thereof between its circular edge and the rivets 10 to be spaced from the member 8 of the shoe as is clearly shown in Fig. 2 of the drawing. 95

At the front middle portion of the plate 9 the member 8 of the shoe is provided with a vertical opening 11 which is for the reception of a screw 12 of considerable length which is inserted through an opening 13 in the plate 14 of aluminum or other suitable 100 metal, which plate is of a size and shape in outlines to coincide with the outlines of the rear portion of the shoe member 8 on the upper surface of which said plate rests. The heel of the shoe is designated as a whole by 105 the reference numeral 15, and is by preference made of aluminum on account of its lightness, durability and strength.

As is clearly shown in Figs. 2 and 3 of the drawing, the heel 15 is solid from its base 110

upwardly to a point near its juncture with the shoe and has between its upper solid portion and its upper end a chamber or cavity 16 formed for the purpose of still further decreasing the weight of the heel. At its rear upper portion the heel 15 is provided with an inwardly extended ledge 17 which has its forward or front edge curved as is clearly shown in Fig. 3 of the drawing. This ledge is wedge shaped as shown in Fig. 2, that is to say, it tapers from its rear portion forwardly and is for the purpose of engaging or interlocking with the rear portion of the plate 9 which is slightly deflected downwardly as shown at 18 in Fig. 2 of the drawing. The solid portion of the heel is provided centrally thereof with a vertical screw-threaded opening 19 for the reception and engagement of the screw 12 when the heel is placed in position on the shoe and said screw is tightened. The plate 14 extends forwardly of the front edge of the upper portion of the heel as is clearly shown in Fig. 2 and thus serves to reinforce the shank of the shoe at said point and thereby prevent bending of the same which ordinarily occurs.

It will be understood that the plate 14 overlies the insole and the inturned portions 30 of the counter and upper of the shoe and that when the heel is positioned as shown in Fig. 2 said parts will be tightly clamped between the plate 14 and the upper portion of the heel in which position the heel will be securely held by means of the screw 12. A piece of felt or leather 20 can be placed on the upper surface of the plate 14 if desired, so as to prevent the hosiery of the wearer coming in contact with said plate.

40 The base or lower end of the heel 15 is provided with a substantially horse-shoe shaped recess 21 for the reception of a similarly shaped washer or piece of leather 22, which can be positioned in said recess so as to be tightly fitted therein and with its lower surface flush with the base of the heel, which base is provided about centrally therein with a vertical screw-threaded opening 23 for the reception of a small screw 50 24 used for securing in place on said base a top-lift 25 of leather or other suitable material, and an aluminum or metal disk 26 which is interposed between the top-lift 25 and the base and is used to hold more securely the washer or piece of fiber 22 or the like in the recess 21 of the heel. This washer of fiber or the like is employed for the reception of nails or spikes 27 driven through the top-lift 25 at the edge of the 60 disk 26 and into the washer 22 so as to firmly secure the top-lift in position.

By the foregoing construction and arrangement of the parts, it will be under-

stood and clearly seen that the heel will be closely and securely held in contact with the 65 heel portion of the shoe and in such a manner that there will be no gapping or separation of the heel from the shoe at either its front or rear portion, and that any turning movement of the heel will be absolutely prevented. 70

It is obvious that the heel can be made in all the different shapes and can be enameled, or covered with material to match the shoe or otherwise treated externally for appearance's sake. 75

Having thus fully described our invention, what we claim as new and desire to secure by Letters Patent is—

1. A shoe comprising a heel having at its 80 upper rear portion within the walls thereof a forwardly extended ledge and with a vertically disposed screw-threaded opening, a plate secured on the lower surface of the heel portion of a shoe and having its rear 85 portion free of the shoe to engage said ledge, another plate located on the inner surface of the heel portion of the insole and having an opening therein to register with the opening in the heel and a screw extended 90 through the opening in the last named plate, the insole and engaging the opening in the heel.

2. A shoe comprising a heel having at its 95 upper rear portion within the walls thereof of a forwardly extended ledge, the same being tapered forwardly, the heel also having a vertically disposed screw-threaded opening located in front of said ledge, a plate secured on the lower surface of the 100 heel portion of a shoe and having its rear portion free of the shoe to engage said ledge, another plate located on the inner surface of the heel portion of the insole and coinciding in outlines therewith, said plate 105 having an opening to register with the opening in the heel and extended forwardly of the front upper portion of the heel and a screw extended through the opening in the last named plate, the insole and engaging 110 the opening in the heel.

3. A shoe consisting of a metal heel having in its base a segmental recess and a vertical screw-threaded opening, a washer of fiber or the like closely fitted in said recess 115 with its outer surface about flush with the base of the heel, an apertured metal plate located on the base of the heel with its opening in register with the opening in the latter, a top-lift located on the last named 120 plate and having an opening therein to register with the other named openings and a screw located in said openings.

AUGUST WEDEIN.
JOHN PERCY STEVENS.
